UNITED STATES PATENT OFFICE

2,662,673

SLEEVE EXPANDER AND/OR FORMER

Yervant Amber, Los Angeles, Calif.

Application May 10, 1951, Serial No. 225,563

5 Claims. (Cl. 223—74)

1

This invention belongs to that general class of devices known as clothes pressing auxiliaries and relates particularly to means for pressing garment sleeves without leaving any creases whatsoever in that such devices are forms which readily conform to the shape of garment sleeves and receive their pressed condition by a steaming and cooling process. The devices hold the cloth of the sleeve in a taut manner automatically so that an operator has both hands free to smooth the wrinkles and thus make a complete and finished press with a minimum of effort.

The invention has among its objects the production of a means of the kind described, or similar means, that is simple, durable and compact in structure, inexpensive to make and manufacture, dependable and efficient in use and service; and a device that is convenient to employ and handle and which has proven very satisfactory in use whenever and wherever found applicable.

One of the important objects is to eliminate the required hand pressures necessary in present types of pelican type sleeve expanders and formers and thus make it easy for the operator to smooth out the wrinkles with his hands before the steaming operation in that an operator can do much better work and in less time than with the well known types since his hands are free and do not have to be employed in applying pressure to the expander or former. In applicant's device, resilient means are employed for automatically expanding the former and for limiting degrees of pressure.

Other objects, advantages and features of this particular invention will appear from a careful perusal of the accompanying drawings, the subjoined and detailed description, the preamble of this specification, and the claims appended hereto.

Below, applicant describes one of the preferable forms of his invention in order to teach the art thereof and show how to make and use the same, but it is to be understood that the drawings and description thereof are not to limit the invention in any sense whatsoever except as the same may be limited by the prior art.

In the drawings:

Figure 1 is a side elevational view of the sleeve expander or pressing form;

Figure 2 is a plan view thereof;

Figure 3 is an enlarged vertical sectional view of the handle portion of the expander and which clearly shows the interior construction and the 55 positioning of its various parts;

2

Figure 4 is a vertical sectional view taken substantially along the line 4—4 of Figure 3.

The particular form of the invention, as illustrated, comprises the main supporting arm 1 having the handle portion 2, and the under pivoted arm 3; these parts forming a pelican type sleeve former which is a name now common in the trade because of its shape which is in the form of the bills of a pelican bird. Both arms have their distal ends rounded so that they can easily enter the sleeve of a jacket or coat. The handle has a rounded chamber portion 4 in which is sufficient room to accommodate the lower end of a catch or latch lever 5, a portion of a control lever 6 and one end of a tensile spring 7, as shown.

The control lever 6 is pivoted to the handle at 8 and has a portion 9 which overlies the handle 2 and which is secured to a wooden gripping means 10. The gripping means 10 and the arms 1 and 3 may be made of any suitable material which is non-heat conducting so as to eliminate sweating and accumulation of moisture. Wood has been found satisfactory in that it does not sweat and is not corrodible so as to cause stains or other marks which might soil or injure the fabric being pressed. One or more non-rust rivets 11 are employed for holding the gripping means 10 to the control lever 6. This lever extends from the chamber 4 in a gentle arc as indicated at 12 and its end is pivoted to the under arm 3 at 13. At the top portion toward the handle of the device, the under arm is provided with a groove 14 to neatly accommodate the slightly curved element 12. The element 12 and the two arms have substantially the same arc formation so as to agree with the average shape of sleeves and also to form a neat compact article.

40 The arc portion 15 of the control lever has a plurality of teeth 16 which are adapted to be engaged by the dog or web portion 17 which bridges the top portion of the latch lever 5 between its legs 18 and 19, see Fig. 4. The lower portion of this lever is pivoted at 20 so that the dog 17 at the base of the web can be made to engage any of the teeth 16 and thus hold the under arm 3 in any position desired, so as not to exceed the stretch limit of the garment sleeve and thus over stretch it and deform it. The under arm 3 is constantly urged away from its supporting arm 1 by the tensile spring 7 which has its ends anchored at the rivet 21 in the bore 22 and at the hole 23 of the control lever portion or end of the extension 12. The expansion of the device or arms must be limited in

order to prevent damage and deformity of such material as knitted goods and crepe etc.

It is, of course, understood that various changes and modifications may be made in the details of form, style, design, materials and construction of the whole or any part of the specifically described embodiment of this invention without departing from the spirit thereof; such changes and modifications are considered as being within the scope of the following claims.

I claim:

1. In an automatic stretcher device for garment sleeves and the like which comprises a principal top supporting arm with a handle portion at its rear end, a control lever pivoted to a portion of the handle and having an offset portion extended under the top supporting arm, a secondary arm pivoted to the forward end of the control lever, spring means in the handle portion which constantly forces the arms apart, and lever means pivoted to the handle which can be set to limit the separation of the arms, and said control lever having another offset rear end portion positioned over the handle.

2. In a device for expanding the sleeves and similar parts of garments, the device having a main supporting arm with a handle portion at an end thereof, an offset control lever having an intermediate portion pivoted to the handle portion, the lever having a relatively short length over the handle portion and a long arc-like portion beneath the supporting arm, an under arm having a portion intermediate its ends which is pivoted to the forward end of the arc-like portion, a spring in the handle having one end fixed to the handle and the other end fixed to the lever at the arc-like portion thereof and which spring is constantly urging the arms apart, and dog means which limit the distance of separa-

tion of the arms but allow the arms to be brought together.

3. The device recited in claim 2 wherein the dog means consists of a pivoted lever which extends upwardly from the handle and through which the control lever passes, the pivoted lever having a web thereon which serves as a dog, and a rounded portion on the control lever having teeth on the outer portion thereof which are adapted to be engaged by the dog so that the control lever is always free to be moved in a direction to bring the arms together.

4. In a pelican type sleeve former having a pair of curved arms in longitudinal abutment, link means pivoted to an end of one of the arms and having an end portion which is pivoted to the other arm intermediate the ends thereof, the link means passing through said end of one of the arms and extending over a portion thereof to form a gripping means so that the arms can be worked in scissor fashion, and spring means attached to one of the arms and to the link means for automatically forcing the arms apart.

5. The sleeve former recited in claim 4 wherein in a latch lever is pivoted at the said one of the arms and which makes contact with a portion of the link means at various points when moved rearwardly, the latch lever when in operative position functioning to limit the expansion of the sleeve former to various degrees.

YERVANT AMBER.
